H. H. Hansen

Attorney.

UNITED STATES PATENT OFFICE.

THOMAS CHRISTIAN THOMSEN, OF COPENHAGEN, DENMARK, ASSIGNOR TO MESSRS. KOFOLD, HAUBERG, MÅSTRAND & HELWEG, AKTIESELSKABET TITAN, OF COPENHAGEN, DENMARK.

CENTRIFUGE MAINLY FOR PURIFYING OR SEPARATING LIQUIDS FROM IMPURITIES CONTAINED.

Application filed April 9, 1925, Serial No. 21,853, and in Denmark April 10, 1924.

For separating liquids, for example lubricating oils from water and solid impurities centrifugal separators are generally employed which are mostly arranged similar 5 to the known milk separators, that is with a drum in which the centrifugal separation is performed, while there are discharge pipes for the oil and for the water separated; sometimes also an overflow pipe is 10 provided.

The solid impurities are deposited along the inner side of the drum, wherefore the latter has, from time to time, to be cleaned of the scale forming thereon. The present 15 invention relates to an arrangement for performing such cleaning of the centrifuge drum in an easy and convenient manner.

In the accompanying drawing the invention has been exemplified in a constructional 20 form; Fig. 1 is a vertical, longitudinal section.

Fig. 2 is a similar view of the lower part of the apparatus with the cleaning means partly raised.

25 In the drawing all parts which are not absolutely necessary for the explanation of the invention have been omitted. Thus, for example, the gear for driving the drum has not been shown, nor the stationary casing 30 and the various discharge nozzles.

In the drawing 1 is the cylindrical wall of the drum, 2 is its bottom having the shape of an inverted funnel, and 3 is its detachable top.

35 Into the drum is fitted an inset, the central tube 4 of which is mounted with its lower part 5 above the bottom 2 of the drum, both the tube 4 and the lower part 5 being

provided in the known manner with ribs 6.

The essential feature of the present invention consists in this that the lower part 5 of the inset terminates in an annular scraper edge 7 which lies close against the internal cylindrical part of the drum.

The solid particles will be deposited along 45 the wall of the drum and may be readily removed by simply removing the top 3, and lifting the inset. The scraper edge will then scrape the scale of impurities off the inside of the drum and thereby collect 50 and remove all solid particles deposited.

Having now described my invention, what I claim as new and desire to secure by Letters Patent is:

1. A centrifugal separator for purifying 55 or separating liquids from impurities contained or separating mixtures of light and heavier liquids, comprising a drum, an inset in the drum, said inset being normally slightly raised above the bottom of said 60 drum and adapted to be lifted up therein and out therefrom, a scraper edge formed on the lower part of said inset and reaching close up to the inside wall of said drum.

2. A centrifugal separator comprising a 65 cylindrical drum, a closed bottom on the drum, a removable internal member mounted in the drum, and an annular bottom part carried on the said internal member and having a circular peripheral scraping edge 70 for engaging the internal cylindrical wall of the drum and removing heavier impurities from said wall as the said member is raised from the drum.

In testimony whereof I affix my signature
THOMAS CHRISTIAN THOMSEN.

THOMAS CHRISTIAN THOMSEN, OF COPENHAGEN, DENMARK, ASSIGNOR TO MESSRS. KOFOLD, HAUBERG, MARSTRAND & HELWEG, AKTIESELSKABET TITAN, OF COPENHAGEN, DENMARK.

CENTRIFUGE MAINLY FOR PURIFYING OR SEPARATING LIQUIDS FROM IMPURITIES CONTAINED.

Application filed April 9, 1925, Serial No. 21,853, and in Denmark April 10, 1924.

For separating liquids, for example lubricating oils from water and solid impurities centrifugal separators are generally employed which are mostly arranged similar to the known milk separators, that is with a drum in which the centrifugal separation is performed, while there are discharge pipes for the oil and for the water separated; sometimes also an overflow pipe is provided.

The solid impurities are deposited along the inner side of the drum, wherefore the latter has, from time to time, to be cleaned of the scale forming thereon. The present invention relates to an arrangement for performing such cleaning of the centrifuge drum in an easy and convenient manner.

In the accompanying drawing the invention has been exemplified in a constructional form; Fig. 1 is a vertical, longitudinal section.

Fig. 2 is a similar view of the lower part of the apparatus with the cleaning means partly raised.

In the drawing all parts which are not absolutely necessary for the explanation of the invention have been omitted. Thus, for example, the gear for driving the drum has not been shown, nor the stationary casing and the various discharge nozzles.

In the drawing 1 is the cylindrical wall of the drum, 2 is its bottom having the shape of an inverted funnel, and 3 is its detachable top.

Into the drum is fitted an inset, the central tube 4 of which is mounted with its lower part 5 above the bottom 2 of the drum, both the tube 4 and the lower part 5 being

Certificate of Correction.

It is hereby certified that in Letters Patent No. 1,603,726, granted October 19, 1926, upon the application of Thomas Christian Thomsen, of Copenhagen, Denmark for an improvement in "Centrifuge Mainly for Purifying or Separating Liquids from Impurities Contained," an error appears requiring correction as follows: In the grant and in the heading to the printed specification, assignment, the name of the first-mentioned assignee should have been written and printed as *Kofold* instead of "Kofold," as shown by the records of assignments in this office; and that the said Letters Patent should be read with this correction therein that the same may conform to the record of the case in the Patent Office.

Signed and sealed this 21st day of December, A. D. 1926.
